GRINDING WHEEL

Application December 7, 1945, Serial No. 633,334

Leopold H. Metzger and Wilson B. Muse, Chicago, Ill., and Fred J. Pease, Wauwatosa, Wis., as

signers, by mesne assignments, to Super-Cut, Inc., a corporation of Illinois

4 Claims. (Cl. 51-209)

The present invention relates to grinding wheels. More particularly the invention relates to that type of grinding wheel which is adapted to be driven at a comparatively high speed by way of a depending power driven shaft, serves to form a smooth surface of desired or predetermined contour on a work piece, such, for example, as a lens, and as its principal components or parts comprises a hub having centrally disposed means whereby it may be connected to the lower end of the shaft, an intermediate web extending outwards from the hub, and a cylindrical sleeve-like rim having the central portion thereof connected to the outer marginal portion of the web and embodying at its lower end a concentrically positioned ring of abrasive material, such as diamond particles in a metallic or other matrix.

In using a grinding wheel of this type it is necessary to employ a coolant in order to prevent overheating of the ring of abrasive material and cracking of the work piece, especially when the latter is a lens blank which is formed of glass. It has heretofore been proposed to apply the coolant by directing it in stream form against the outer periphery of the abrasive ring and the subjacent portion of the work piece. In practice it has been found that when the coolant is applied in this manner it does not form a continuous film under the abrasive ring due to the fact that the wheel in response to drive causes the coolant to rotate with the wheel and flow outwards by centrifugal force. When the coolant does not form a continuous film under the abrasive ring there is a marked or pronounced tendency for the ring to heat and result in cracking or fracture of the work piece. Furthermore, the ground work piece particles have a tendency to remain under the ring and hence scratch the work piece during drive of the wheel and preclude the formation of the desired smooth surface on the work piece.

One object of the instant invention is the provision, in connection with a grinding wheel of the type under consideration, of novel means whereby the coolant is supplied around the lower portion of the inner periphery of the cylindrical sleeve-like rim in order that it flows outwards by centrifugal force under the abrasive ring and serves not only to provide a continuous film between the ring and the subjacent portion of the work piece and thus effect maximum cooling, but also to flush or wash away the ground particles of the work piece.

Another object of the invention is to provide a grinding wheel of the last mentioned character

and having means for maintaining the abrasive ring in its proper position and in a desired relationship to the work piece, such as a cylindrical sleeve-like rim having a central portion connected to the outer marginal portion of the web and embodying at its lower end a concentrically positioned ring of abrasive material.

Another object of the invention is to provide a grinding wheel of the type and character under consideration in which the coolant supplying means is adapted to receive the coolant from a downwardly extending stationary supply tube that is disposed in close proximity to the power driven shaft for the wheel and projects in the direction of the upper surface of the web of the wheel, and is in the form of an annular series of spaced apart ducts which are formed in, and extend downwards completely through, the outer marginal portion of the wheel web.

Another object of the invention is to provide a grinding wheel of the type and character under consideration in which the ducts constituting the coolant supplying means are spaced equidistantly apart and are downwardly inclined in a direction opposite to the direction of rotation of the wheel.

Another object of the invention is to provide a grinding wheel of the aforementioned character in which the portions of the upper surface of the web that are disposed between the upper ends of the ducts are downwardly inclined in a direction opposite to the direction of rotation of the wheel in order that the coolant after discharge from the supply tube is directed into the upper ends of the ducts and such ends of the ducts constitute or form scoops which direct the coolant downwards for passage or flow through the ducts.

Another object of the invention is to provide a grinding wheel of the type and character under consideration in which the inner peripheral portion of the upper end of the sleeve-like rim is under-cut in order to provide a downwardly flared annular surface which, in connection with operation of the grinding wheel, confines the coolant that is discharged by the supply pipe so that it flows for the most part into the upper ends of the ducts constituting the coolant supply means.

A further object of the invention is to provide, in connection with a grinding wheel of the type under consideration, a novel hood structure which precludes the coolant, prior to passage into the ducts, from flowing outwards over the upper end of the rim in response to the action of centrifugal force.

A still further object of the invention is to provide a grinding wheel which is an improvement upon, and eliminates the defections of, previously designed grinding wheels and is characterized by high efficiency as well as simplicity of design.

Other objects of the invention and the various advantages and characteristics of the present grinding wheel will be apparent from a consideration of the following detailed description.

The invention consists in the several novel features which are hereinafter set forth and are more particularly defined by claims at the conclusion hereof.

In the drawing which accompanies and forms a part of this specification or disclosure and in which like numerals and letters of reference denote corresponding parts throughout the several views:

Figure 1 is a perspective of a grinding wheel embodying the invention, certain parts being broken away and other parts being shown in section for purposes of illustration;

Figure 2 is an enlarged vertical section showing the grinding wheel in operative or grinding relation with a work piece on a rotary work holder, and illustrating in detail the construction and design of the wheel proper and the hood structure;

Figure 3 is a cross section taken on the line 3—3 of Figure 2; and

Figure 4 is a section taken on the line 4—4 of Figure 3 and illustrating in detail the angular arrangement of the ducts in the outer marginal portion of the rim of the wheel and the portions of the upper surface of the wheel rim that extend between the upper ends of the ducts.

The grinding wheel which is shown in the drawing constitutes the preferred form or embodiment of the invention. It is adapted to be driven at a comparatively high speed by way of a depending power driven shaft *s* and serves as described hereinafter more in detail, to provide a smooth surface of desired or predetermined contour on work piece *w*. The latter is illustrated in the drawing as being a lens blank of glass, although it is to be understood that it may be any other object to be ground. The work piece *w* is suitably mounted on a rotary cup-shaped holder *h* which embodies a depending centrally disposed drive shaft *d* whereby it may be driven. In connection with a work piece driving operation it is contemplated that the holder for the work piece will be driven in one direction and the shaft *s* for driving the grinding wheel will be driven in the opposite direction. For purposes of the present disclosure it will be considered that the cup-shaped work piece holder *h* will be driven in a counterclockwise direction and the shaft *s* together with the grinding wheel will be driven in a clockwise direction. The shaft *s* overlies the cup-shaped holder and is driven by an electric motor or other means (not shown). If the grinding wheel is used to grind a lens blank the shaft *s*, in connection with drive thereof, will be oscillated as well understood in the art. Since the means for driving the work holder *h* and the means for driving and oscillating the grinding wheel shaft *s* form no part of the present invention they are not illustrated. As its principal parts or components the grinding wheel comprises a vertically elongated hub *5*, a web *6* and a cylindrical sleeve-like rim *7*.

The hub *5* has a longitudinally extending, full length, downwardly tapered socket *8* in which the lower end of the power driven shaft *s* fits snugly when the grinding wheel is in its operative position with respect to the shaft. Such lower end of the shaft *s* is downwardly tapered conformably to the socket *8*. A nut *9* on a reduced externally threaded stem *10* on the lower extremity of the shaft *s* serves to urge the hub *5* of the grinding wheel upwards into clamped and fixed relation with the lower end of the shaft *s*. When the nut *10* is removed the grinding wheel may be re-

moved from the shaft by driving it or shifting it downwards.

The web *6* of the grinding wheel is formed integrally with, and projects outwards from, the central and lower portions of the hub. It serves to connect the rim *7* for drive by the hub and embodies in its outer marginal portion an annular series of equidistantly spaced elongated straight ducts *11* which, as hereinafter described more in detail, serve to supply a coolant, such as water or other liquid, from a coolant supply tube *12* onto the lower portion of the inner periphery of the rim *7*.

The rim *7* surrounds, and is of materially greater height than, the web *6*. The central upper portion of the rim is suitably connected to the outer marginal portion of the web, such, for example, as by being formed integrally therewith. The upper portion of the rim projects a comparatively short distance above the upper surface of the web and surrounds, and is in spaced relation with, the upper end of the hub *5*. The lower portion of the rim projects an appreciable distance beneath the web and embodies on its lower extremity a concentrically positioned ring *13* of abrasive material, such, for example, as fine mesh diamond particles in a metallic or other matrix. The ring is fixedly connected to the lower extremity of the rim in any suitable manner. If the material of which the ring is formed consists of diamond particles in a metallic matrix the ring is secured in fixed relation with the lower extremity of the rim by fusing the metallic matrix to the rim, provided that the rim is formed of metal which is compatible with the matrix. As shown in Figure 2, the outer and inner diameters of the ring of abrasive material correspond to the outer and inner diameters of the lower portion of the rim, i. e., the portion that projects beneath the web *6* of the wheel. If desired, such lower portion of the rim may be formed separately from the upper portion and removably secured thereto by a screw thread connection *14*. In connection with use of the grinding wheel the work holder *h* is positioned so as to bring the upper surface of the work piece *w* into contact with a portion of the ring *13*, as shown in Figure 2. During counterclockwise drive of the work holder and clockwise drive and also oscillation of the shaft *s*, the ring *13* of abrasive material revolves around and traverses the upper surface of the work piece and grinds it so that it has the desired smoothness and contour.

The coolant supply tube *12* extends substantially vertically and is arranged in close proximity to that portion of the power driven shaft *s* that is disposed immediately above the grinding wheel. The upper or inlet end of the tube is connected to any suitable source of coolant supply, such for example, as a reservoir or tank (not shown) and the lower or discharge end of the tube directly overlies the upper surface of the wheel web *6*, as shown in Figure 2. When the wheel is in operation it is contemplated that the tube *12* will supply a constant stream of the coolant onto the upper surface of the web. The ducts *11* in the outer marginal portion of the web conduct the coolant from the upper surface of the web downwards and supply it around the lower portion of the inner periphery of the cylindrical sleeve-like rim *7* of the wheel. As soon as the coolant flows onto said lower portion of the inner periphery of the wheel rim it swirls downwards in the form of a continuous film. As soon

5

as the coolant reaches the lower inner edge of the ring 13 of abrasive material it is flung outwards by centrifugal force under and outwards across the ring. The coolant, in response to the action of centrifugal force, forms a continuous film between the lower surface of the ring and the subjacent portion of the work piece and not only effects efficient cooling of the ring, but also serves to flush or wash away the particles which are ground from the work piece. The ducts 11 extend approximately at an angle of 60° with respect to the lower surface of the wheel web 6, as shown in Figure 4, and are downwardly inclined in a direction opposite to the direction of rotation of the wheel. By so inclining the ducts the coolant is forced downwards through the ducts by a cam or wedge type action. The portions of the upper surface of the web 6 that are disposed between the upper ends of the ducts 11 are downwardly inclined in a direction opposite to the direction of rotation of the wheel in order that the coolant, after discharge from the supply tube 12, is efficiently and effectively directed into the upper ends of the ducts for downward flow through the ducts onto the lower portion of the inner periphery of the rim 1. By reason of the fact that the trailing portions of the upper ends of the ducts are at a higher level or elevation than the lower or trailing ends of the aforementioned portions of the upper surface of the web such portions of the upper ends of the ducts form scoops which face in the direction of drive or rotation of the wheel and operate during drive of the wheel to direct the coolant downwards into and through the ducts. Preferably the outer portions of the ducts are in substantial alignment with the lower portion of the inner periphery of the rim. As shown in the drawing the upper and lower ends of the ducts are spaced equidistantly from the axis of the wheel and as a result the longitudinal center lines of the ducts lie substantially in an imaginary cylindrical surface which is concentric with the cylindrical rim 1. Because of the specific arrangement or positioning of the ducts 11 the coolant is discharged in such manner onto the inner periphery of the lower portion of the rim that it swirls around and substantially completely covers said inner periphery. In order to confine the coolant so that after discharge thereof from the supply tube it flows onto the upper surface of the wheel web and into the ducts without appreciable or pronounced spillage over the upper projecting portion of the rim, the inner peripheral portion of the upper end of the rim is under-cut in order to provide a downwardly flared annular surface 15. The latter overhangs to a small extent the upper ends of the ducts and confines the coolant on the upper surface of the wheel web so that it is precluded from being flung outwards by centrifugal force.

In addition to the parts heretofore mentioned the grinding wheel comprises a composite hood structure 16. This structure serves to prevent the coolant from flowing outwards over the upper end of the wheel rim 1 and comprises a lower member 17 and an upper member 18. The lower member is hemispherically or dome shaped and is preferably in the form of a sheet metal stamping. It overlies the grinding wheel proper and embodies in the upper central portion thereof a circular hole 19 through which the power driven shaft *s* extends. As shown in Figure 2, the hole 19 is in concentric relation with the shaft and the diameter is approximately twice that of the

6

adjacent portion of the shaft. A cylindrical flange 20 is connected to, and extends upwards from, the hole defining portion of the lower hood member 17. The lower marginal portion of such member surrounds the upper end of the wheel rim 1 and is removably secured in place by way of screws 21. The latter extend through holes in the lower marginal portion of the hood member 17 and into radially extending threaded sockets 22 in the upper end of the rim. The upper member 18 of the hood is stationary and surrounds the shaft *s* at a point above the lower member 17 of the hood structure. It is suitably supported from above and embodies at its lower end an externally disposed inverted U-shaped flange 23 which, as shown in Figure 2, is arranged in straddled relation with the flange 20 on the upper central portion of the lower member 17. The supply tube 12 for the coolant extends between the upper member 18 and the shaft *s*. During use of the grinding wheel the hood structure serves, as previously pointed out, to prevent out-flow of the coolant over the upper end of the wheel rim 1. In connection with removal of the wheel proper from the shaft *s* the upwardly projecting flange 20 on the upper central portion of the lower member 17 slides out of interfitting relation with the inverted U-shaped flange 23 on the lower end of the upper member 18 in connection with downward shift of the wheel proper.

During a grinding operation the work holder *h* is driven in a counterclockwise direction by the drive shaft *d* and the grinding wheel is driven in a clockwise direction and is also oscillated or rocked back and forth over the work piece by the power driven shaft *s* as hereinbefore pointed out. In response to drive and oscillation of the grinding wheel the ring 13 grinds the upper surface of the work piece so that it has the desired contour and polish or smoothness. The coolant which is supplied in stream form onto the upper surface of the web 6 of the wheel by the supply tube 12 flows downwards over the portions of the upper face of the web that are between the upper ends of the ducts 12. It then enters and flows downwards through the ducts. After flowing through the ducts the coolant swirls around the lower portion of the inner periphery of the wheel rim and finally in response to the action of centrifugal force flows outwards in film form under the ring 13 of abrasive material. As the coolant flows under the ring it cools the latter and the work piece and flushes or washes away the ground particles of the work piece.

The herein described grinding wheel is highly efficient due to the fact that it includes novel means whereby the coolant is supplied around the lower portion of the inner periphery of the cylindrical sleeve-like rim in order that it flows outwards by centrifugal force under the abrasive ring and serves not only to provide a continuous film between the ring and the subjacent portion of the work piece, but also to flush or wash away the ground particles of the work piece. Because of the design and construction of the wheel the latter may be produced at a comparatively low cost.

It is to be understood that the subject grinding wheel although it has been illustrated and described in connection with the grinding of a work piece in the form of a lens blank, has other capabilities of use. It is also to be understood that the invention is not to be restricted to the details set forth since these may be modified within the scope of the appended claims without

departing from the spirit and scope of the invention.

Having thus described the invention what we claim as new and desire to secure by Letters Patents is:

1. A grinding wheel adapted to be driven about its axis in one direction and comprising a hub, a web connected to and extending outwards from the hub, and a cylindrical rim having one portion thereof extending around and connected to the outer marginal portion of the web and in addition having one of its end portions projecting in one direction beyond one exposed surface of the web and provided on its outer extremity with abrasive material, said web having extending completely therethrough an elongated straight duct for conducting to the inner periphery of said one end portion of the rim a coolant that is supplied to the other exposed surface of the web, said duct having the receiving and discharge ends thereof spaced substantially equidistantly from the axis of the wheel, being inclined from the receiving end thereof to its discharge end in a direction opposite to the direction of drive of the wheel, and having at its said receiving end means forming a scoop facing in the direction of drive of said wheel and shaped and arranged so that during drive of the wheel it serves positively to direct into the receiving end of the duct the coolant that is supplied to said other exposed surface of the web.

2. A grinding wheel adapted to be driven about its axis in one direction by a substantially vertical power driven shaft and comprising a hub having associated therewith means for connecting it to the shaft, a web connected to and extending outwards from the hub and a cylindrical sleeve-like rim having the upper portion thereof extending around and connected to the outer marginal portion of the web and having its lower end portion projecting downwards beyond the lower surface of the web and provided at its lower extremity with abrasive material, said web having formed therein an open ended straight duct arranged so that the upper and lower ends thereof are spaced equidistantly from the axis of the wheel, inclined downwards in a direction opposite to the direction of drive of the wheel and adapted to conduct to the inner periphery of said lower end portion of the rim a coolant that is supplied to the upper surface of the web, the portion of the upper surface of the web that is immediately ahead of the upper end of the duct being downwardly inclined in the same direction as the duct in order that the trailing portion of said upper end of the duct is higher than the leading portion and forms a scoop that faces in the direction of drive of the wheel and serves to direct the coolant downwards into the duct.

3. A grinding wheel adapted to be driven about its axis in one direction by a power driven shaft and comprising a hub, a web connected to and extending outwards from the hub and a cylindrical sleeve-like rim having one portion thereof extending around and connected to the outer marginal portion of the web and in addition having one end portion thereof projecting in one direction beyond one exposed surface of the web and provided on its outer extremity with abrasive material, said web having means for conducting through it to the inner periphery of said one end portion of the rim a coolant that is supplied to the other exposed surface of the web, said means including surfaces that are inclined toward said one exposed surface of the web in a direction directly opposite to the direction of drive of the wheel.

4. A grinding wheel adapted to be driven about its axis in one direction by a power driven shaft and comprising a circular body member embodying surfaces at opposite ends thereof, provided with abrasive material adjacent one of said surfaces, adapted to have a fluid coolant delivered to the other surface, and having formed therein between the two surfaces a straight open ended duct adapted to conduct to the abrasive material the coolant that is supplied to said other surface of the body member, said duct being inclined from its receiving end to its discharge end in a direction opposite to the direction of drive of the wheel, the portion of said other surface of the body member that is immediately ahead of the receiving end of the duct being inwardly inclined towards and into said receiving end of the duct in order that the trailing portion of said receiving end of the duct is outwards of the leading portion and defines a scoop that faces in the direction of drive of the wheel and serves positively to direct through the duct the coolant that is supplied to said other surface of the body member.
